US00D817206S

(12) **United States Design Patent** (10) Patent No.: **US D817,206 S**
Lee et al. (45) Date of Patent: ** May 8, 2018

(54) **DETECTOR FOR HOME AUTOMATION DEVICES**

(71) Applicant: **LG ELECTRONICS INC.**, Seoul (KR)

(72) Inventors: **Hophil Lee**, Seoul (KR); **Kyoungjoung Kim**, Seoul (KR); **Jaewon Jeong**, Seoul (KR)

(73) Assignee: **LG Electronics Inc.**, Seoul (KR)

(**) Term: **15 Years**

(21) Appl. No.: **35/502,278**

(22) Filed: **Jul. 7, 2016**

(80) **Hague Agreement Data**

Int. Filing Date: **Jul. 7, 2016**

Int. Reg. No.: **DM/092279**

Int. Reg. Date: **Jul. 7, 2016**

Int. Reg. Pub. Date: **Jan. 13, 2017**

(30) **Foreign Application Priority Data**

May 31, 2016 (KR) 30-2016-0026398

(51) **LOC (11) Cl.** **10-05**

(52) **U.S. Cl.**

USPC **D10/106.7**

(58) **Field of Classification Search**

USPC D10/49, 50, 106.7, 106.8; D13/162, D13/162.1, 164, 168

CPC H04R 1/023

(57) **CLAIM**

The ornamental design for a detector for home automation devices, as shown and described.

DESCRIPTION

1. Detector for home automation devices

1.1 is a front perspective view.

1.2 is a front view.

1.3 is a rear view.

1.4 is a right side view.

1.5 is a left side view.

1.6 is a top view.

1.7 is a bottom view.

1.8 if an exploded view.

The broken lines depict unclaimed environmental subject matter.
